UNITED STATES PATENT OFFICE.

FRANK McDANIEL, OF DETROIT, MICHIGAN.

COIN-CONTROLLED LOCK.

Application filed February 19, 1923. Serial No. 619,960.

To all whom it may concern:

Be it known that I, FRANK McDANIEL, a citizen of the United States, residing at Detroit, in the county of Wayne and State 5 of Michigan, have invented certain new and useful Improvements in Coin-Controlled Locks; and I do declare the following to be a full, clear, and exact description of the invention, such as will enable others skilled 10 in the art to which it appertains to make and use the same.

My invention relates to improvements in coin-controlled locks of the type used for instance upon lockers, one object being to 15 provided novel means for holding the bolt of the lock against operation in case an actuator which is associated with said bolt, is moved without inserting a coin to establish a connection between the actuator and 20 bolt to permit operation of the latter.

A further object is to provide a novel form of bolt and actuator of such construction as to permit the edgewise insertion of 25 a coin to form an operating connection be-

tween them.

With the foregoing in view, the invention resides in the novel subject matter hereinafter described and claimed, the description being supplemented by the accompanying drawings.

Figure 1 is an inner side elevation of a lock constructed in accordance with my invention, showing the normally unlocked condition thereof.

Figure 2 is a duplicate of a portion of Fig. 1 with the exception that it illustrates the locking bolt projected.

Figure 3 is a view similar to Fig. 1 but illustrating the relation of parts when an 40 attempt is made to project the bolt without inserting a coin.

Figure 4 is a horizontal sectional view as indicated by line 4—4 of Fig. 1.

Figure 5 is a vertical section on line 5—5 45 of Fig. 4.

Figure 6 is a vertical transverse sectional view on line 6—6 of Fig. 5.

Figure 7 is a perspective view of the bolt and the tumbler which normally prevents 50 projection of said bolt.

Figure 8 is a perspective view of the bolt actuator.

In the drawings above briefly described, I have shown a vertically positioned chan-

nel-shaped plate 1 which may either be a 55 part of a door to be locked by the invention, or may be a separate plate or casing part adapted to be secured to the door. One flange 2 of the plate 1 has been shown as formed with an opening 3 through which 60 the bolt 4 which is horizontally guided in any suitable manner may be projected. In the preferred form of construction, this bolt is of the formation shown most clearly in Fig. 7. In this view, the bolt is shown of 65 channel-shape, being provided with a bottom 5, a comparatively long side wall 6 adjacent the plate 1, and a relatively short side wall 7. A lug 8 extends laterally from the side wall 7 and also extends downward- 70 ly from the bottom 5, the two side walls and said bottom being slotted as indicated at 9 to receive a coin 10. This slot opens through the lower side of the lug 8 and while it opens through the upper edges of 75 the two side walls 6 and 7 and through the wall 6, it does not open through the outer side of the laterally extending part of the lug 8, although it extends some distance into said lug.

Slidably received in the channel of the bolt 4 is a horizontally elongated bolt actuator 11 having a slot 12 which normally registers with the slot 9 to receive the coin 10, when the latter is inserted edgewise 85 through a slot 13 in the plate 1.

For operating the actuator 11, I have shown a common form of cylinder lock 14 having a projecting finger 15 received in a recess 16 in the upper edge of said actuator. The construction (well known) is such that when the key is inserted into the lock 14 and turned to cause retraction of the bolt 4 and its actuator 11, the key is locked in place and cannot be removed. 90 When a coin 10 is inserted however in the registering slots 9 and 12 and the lock 14 is actuated by means of the key to project the bolt, then the key can be removed, leaving the door locked in closed position. 95 When it is desired to again unlock the door, the key is inserted into the lock and the latter is turned to move the actuator 11 in the proper direction for withdrawing the bolt 4. While any suitable connection may be employed between the actuator and bolt for this purpose, I have shown said actuator provided with a depending stud 17 re-

ceived slidably in a slot 18 in the bottom 5 of the bolt 4. While this connection operates to retract the bolt, the stud will merely slide within the slot if an attempt is 10 made to project said bolt without first inserting a coin to establish an operating connection between the actuator and bolt.

In the preferred form of construction, the 15 bolt 4 rests slidably upon a suitable plate 19 secured by screws or the like 20 to the plate 1, this plate being here shown as provided with an annular flange whose horizontal portion 21 constitutes a ledge normally underlying the registering slots in the 20 bolt and actuator. Thus, when a coin is inserted in said slots as shown in Figs. 1, 5 and 6, this coin will be supported by the ledge 21. When the lock 14 is operated to bodily project the actuator 11 of the bolt 4 however, the coin is moved from the ledge 25 and drops into a suitable receptacle (not shown) as will be clear by reference to Fig. 2.

It will be seen from the foregoing that the 25 actuator 11 may be idly moved within the channel of the bolt 4 when no coin is inserted into the device, but to positively prevent projection of the bolt 4 by such idle movement, I provide normally idle bolt-holding means which is moved to an operative position by projection of the actuator within the bolt, to a predetermined extent. In the present showing, this means is in the 30 form of an annular gravity-released tumbler 25 loosely pivoted at 26 to the side wall 6 of the bolt, beyond the lug 8, so that the depending arm 27 of this tumbler, is in the outward path of the actuator 11. The horizontal arm of the tumbler 25 is so disposed 35 that when said tumbler is tilted by outward movement of the actuator, said arm will engage the flange 2 as shown in Fig. 3, thus holding the bolt against projection, unless a coin is inserted. Upon the insertion of this 40 coin however, relative movement of the bolt and actuator is prevented and they are caused to move bodily as a unit and consequently the tumbler 25 will not come into play.

50 Preferably used in connection with the features above described, is a suitable counter 30 which registers the number of times the bolt is projected. I also prefer to provide this bolt with a depending V-shaped lug 31 engageable with a spring arm 32 when the bolt is projected, preventing accidental release of the latter.

From the foregoing, taken in connection 55 with the accompanying drawings, it will be seen that I have provided a simple and inexpensive, yet a highly efficient and reliable lock which may only be operated by the insertion of a coin. Particular attention is directed to the fact that the construction 60 is such as to permit edgewise insertion of

the coin as experience has proven that the coin is much easier to insert in this manner than when it must be moved bodily into a circular opening. Attention is also directed particularly to the novel means employed to prevent accidental projection of the bolt by idle movement of the actuator.

70 As excellent results have been obtained from the details disclosed, they may be followed if desired. However, within the scope 75 of the invention as claimed, numerous minor changes may be made.

I claim:

1. A coin-controlled lock comprising a bolt, an actuator for said bolt movable with 80 respect thereto, said bolt and actuator having spaced shoulders between which a coin may be inserted to operatively connect said bolt and actuator, and normally idle means brought into play by movement of the actuator with respect to the bolt for holding the latter against projection.

2. A coin-controlled lock comprising a bolt, an actuator for said bolt movable with 90 respect thereto, said bolt and actuator having spaced shoulders between which a coin may be inserted to operatively connect said bolt and actuator, and a normally idle bolt-holding tumbler carried by said bolt and having a portion in the path of said actuator 95 for moving said tumbler to operative position upon movement of said actuator with respect to said bolt.

3. A coin-controlled lock comprising a 100 bolt, an actuator for said bolt movable with respect thereto, said bolt and actuator having spaced shoulders between which a coin may be inserted to operatively connect said bolt and actuator, and a gravity-released normally idle tumbler pivoted to said bolt and having a portion in the path of said actuator, whereby idle movement of said actuator with respect to the bolt will move 105 said tumbler to an operative position at which it prevents movement of said bolt.

4. A coin-controlled lock comprising a channel-shaped horizontal bolt and guiding means therefor, a lug extending laterally from one side and downwardly from the bottom of said bolt, the side walls of said bolt and its bottom having a coin-receiving slot which opens through the lower side of said lug and extends into the laterally extending part of said lug, a bolt actuator 115 slideable freely in said channel-shaped bolt and having a slot which opens through its vertical sides and its lower edge, the slots of the bolt and actuator being normally in register to receive a coin, and a fixed ledge 120 under said lug upon which the coin rests when inserted, movement of the actuator and bolt upon the insertion of a coin serving to move the latter from said ledge.

5. A coin controlled lock comprising a 130 channel-shaped horizontal bolt and guiding

means therefor, a lug extending laterally from one side and downwardly from the bottom of said bolt, the side walls of said bolt and bottom having a coin receiving slot 5 which opens through the lower side of said lug and extends into the laterally extending part of said lug, means for supporting

a coin inserted into said slot until the bolt is projected, and a bolt actuator slidably in said channel-shaped bolt and adapted to engage a coin in said slot to project said bolt. 10

In testimony whereof I have hereunto affixed my signature.

FRANK McDANIEL.
